UNITED STATES PATENT OFFICE.

DAVID SNELLING, OF FREEDOM, ILLINOIS.

GOPHER CULTIVATOR.

SPECIFICATION forming part of Letters Patent No. 412,426, dated October 8, 1889.

Application filed April 8, 1889. Serial No. 306,451. (No model.)

To all whom it may concern:

Be it known that I, DAVID SNELLING, a citizen of the United States, residing at Freedom, in the county of La Salle and State of Illinois, have invented a certain new and useful Improvement in Gopher Cultivators, which is fully set forth in the following specification, reference being had to the accompanying drawings, in which—

10 Figure 1 is a plan view of a construction embodying my invention; Fig. 2, a side elevation; Fig. 3, a detail plan section taken on the line 1 1 of Fig. 2; Fig. 4, a detail sectional view taken on the line 2 2 of Fig 2, and Fig. 15 5 a detail view of the arch.

Like letters refer to like parts in all the figures of the drawings.

My invention relates to cultivators, and more particularly to that class known as "gopher cultivators," and has for its object to provide a construction which will permit the shovels and shovel-frame to be freely moved laterally while at work, while at the same time their relation with regard to each other 25 and with regard to the line of draft will always remain the same, thus always preserving an equal distance between the shovels, while at the same time they are always presented at the same angle to the line of draft.

30 To these ends my invention consists in certain novel features, which I will now proceed to describe, and will then particularly point out in the claims.

In the drawings, A represents a cultivator-frame of any approved construction, that 35 shown in the present instance being composed of a main frame *a*, provided with downwardly and outwardly bent axles *a'*, upon which the wheels *a²* are mounted. To the axles *a'* there 40 are connected, by any suitable form of coupling *A'* which will permit of free lateral and vertical movement, the draft-beams or links *B*, located one on each side of the apparatus.

C represents the gopher-frame, which is a 45 rigid frame composed of two similar halves connected by a rigid arch, and to which the rear ends of the draft-beams or links *B* are pivoted. Each half of the gopher-frame *C* is composed of a gopher-beam *C'*, formed in one 50 piece, with the inclined standards *c'* at its ends, to which standards the gopher-shovels

D are attached, said shovels being braced by rods *d*, extending from their forward ends to the standard-tops.

E represents a casting, to the outer face 55 of which the beam *C'* is bolted, said casting being provided with lugs *e* at its rear end, between which the beam is embraced in order to hold it more firmly in position. To the inner face of this casting the handle *C²* is 60 secured by means of a bolt *c²* at its forward end, said handle being supported by means of an upright *C³*, having its lower end bolted to the beam *C'* near its rear end, while its upper end is provided with a series of apertures *c³*, 65 through one of which and through the handle *C²* a bolt *C⁴* passes. By this means the height of the handle may be adjusted.

The casting *E* is provided at its front end with a flange *E'*, standing at an angle to the 70 body, and to the rear face of this flange the lower end of the arch *F* is secured by means of bolts *f*, as shown more particularly in Figs. 3 and 4. Braces *F'* extend from the crown of the arch to the rear of the gopher-beams *C'*. 75

The arch *F* is preferably constructed in two separate parts, the ends overlapping at the crown, as shown in Figs. 1 and 5, and being connected by bolts *f'*, passing through slots *f²*, 80 in order to permit adjustment of the two portions of the arch to increase or diminish the lateral distance between the gopher-beams.

From the front of the flange *E'* there extend forward lugs *e'*, which are perforated for the passage of the bolt *E²*, which forms the 85 pivot between the draft-beam *B* and the gopher-frame *C*. The connection at this point is effected by pivoting to the rear end of the beam *B* a casting *B'*, connected thereto by means of a pivot-bolt *b*, and provided at its 90 forward end with a curved slot *b'*, through which a clamping-bolt *b²* passes into the beam *B*. By reason of this connection the angle of the casting *B'* with relation to the beam *B* may be varied, as desired, to alter the 95 set of the shovels. From the casting *B'* there extend rearward lugs *b³*, which are perforated for the bolt *E²*, and these lugs being inserted between the lugs *e'* on the casting *E*, the bolt *E²* is passed down through the whole of them 100 so as to connect the beam to the gopher-frame.

The arch *F* is provided at the top with a

hook or loop F^2 , by means of which it may be suspended upon the rearwardly-extending central member a of the frame A when not in use, in the manner usual in cultivators of this description.

The apparatus thus constructed operates in the following manner: The cultivator-frame A may be, as hereinbefore stated, any approved form of cultivator-frame, the remainder of the apparatus being designed principally as an attachment thereto. When it is desired to use the gopher attachment, the cultivator-gangs are detached from the frame A, and the draft-beams are coupled to said frame in their place. Now, it will be observed that these draft-beams B are of equal length and substantially parallel, the lateral distance separating their rear ends being about equal to the lateral distance between their front ends. There may, of course, be a slight divergence from this parallelism, and in the drawings I have shown such a slight divergence, which may be increased or diminished, or, indeed, entirely overcome, by the adjustment of the two sections of the arch F, and which is not in any case sufficient to materially affect the operation hereinafter described. It will at once be seen that the gopher-frame C may be moved laterally, as desired, while the machine is in operation, so as to accommodate its position to the row upon which it is operating, and owing to the fact that the said frame is a rigid frame the lateral distance between the shovels will always be the same, no matter what its position may be. At the same time, owing to its connection to the cultivator-frame by means of the two parallel beams B of equal length, the said frame will always maintain the same relative position to the line of draft, and will not assume an angling position, but will always face squarely to the front, as shown in

dotted lines in Fig. 1 of the drawings. The construction of the gopher-frame is, moreover, simple and cheap, and at the same time strong, the castings E serving as a kind of base to which the various portions of the frame are attached and by which they are firmly supported.

It is obvious that various modifications in the details of construction may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. The combination, with the cultivator-frame, of the gopher-frame consisting of two beams provided with shovels and the arch rigidly connecting the same, and the draft-beams, substantially parallel and of equal length and pivoted at their rear ends to the gopher-frame, substantially as and for the purposes specified.

2. The combination, with the gopher-beams, the handles, the arch, and the draft-beams, of the castings E, adapted to receive and support said parts, which are connected thereto, substantially as and for the purposes specified.

3. The combination, with the gopher-frame having apertured lugs e' , of the draft-beams B, the castings B', adjustably connected to the rear end of the draft-beams and provided with apertured lugs b' , and the pivot-bolts E^2 , passing through said lugs, substantially as and for the purposes specified.

DAVID SNELLING.
